(57) **CLAIM**

The ornamental design for a rail for a conveyor system, as shown and described.

DESCRIPTION

FIG. 1 is a front top left perspective view of a rail for a conveyor system showing our new design according to an embodiment.

FIG. 2 is a rear bottom right perspective view thereof.

FIG. 3 is a front view thereof.

FIG. 4 is rear a view thereof.

FIG. 5 is a left view thereof.

FIG. 6 is a right view thereof.

FIG. 7 is a top view thereof.

FIG. 8 is a bottom view thereof.

FIG. 9 is a front top left perspective view of a rail for a conveyor system showing our new design according to an embodiment.

FIG. 10 is a rear bottom right perspective view thereof.

FIG. 11 is a front view thereof.

FIG. 12 is rear a view thereof.

FIG. 13 is a left view thereof.

FIG. 14 is a right view thereof.

FIG. 15 is a top view thereof.

FIG. 16 is a bottom view thereof.

FIG. 17 is a front top left perspective view of a rail for a conveyor system showing our new design according to an embodiment.

FIG. 18 is a rear bottom right perspective view thereof.

FIG. 19 is a front view thereof.

FIG. 20 is rear a view thereof.

FIG. 21 is a left view thereof.

FIG. 22 is a right view thereof.

FIG. 23 is a top view thereof; and,

FIG. 24 is a bottom view thereof.

The broken lines comprising even length dashes showing the remainder of the rail for a conveyor system are unclaimed subject matter and form no part of the claimed design herein. The dot-dashed lines boundary lines form no part of the claimed design herein. The bounds of the claimed design are defined with dot-dashed boundary lines herein when a boundary does not exist at the location of the dot-dashed boundary lines in the article embodying the design. The design extends to but does not include the dot-dashed boundary lines.

The rail for a conveyor system is shown with a symbolic break in its length. The appearance of any portion of the article between the break lines form no part of the claimed design.
